(No Model.)

E. WITTEBORG.
COMBINED TRUNK AND DRESSING CASE.

No. 566,262.

Patented Aug. 18, 1896

UNITED STATES PATENT OFFICE.

ERNEST WITTEBORG, OF BRENHAM, TEXAS.

COMBINED TRUNK AND DRESSING-CASE.

SPECIFICATION forming part of Letters Patent No. 566,262, dated August 18, 1896.
Application filed October 30, 1895. Serial No. 567,392. (No model.)

To all whom it may concern:

Be it known that I, ERNEST WITTEBORG, a citizen of the United States, residing at Brenham, in the county of Washington and State 5 of Texas, have invented certain new and useful Improvement in a Combined Trunk and Dressing-Case, of which the following is a specification.

This invention has reference to a combined 10 trunk and dressing-case of that class in which the body of the trunk is provided with drawers for storing the various articles, while the lid of the trunk is connected to one end of the body of the trunk and provided with a 15 number of drawers and in which the lid is connected at one end by a hinged strap with one end of the body of the trunk, so as to be adapted to be moved into position for closing the body and to be supported in upright position on the same in line with the bottom, so 20 that it forms a proper support for a looking-glass, shelf, and the like.

The invention consists, further, of certain other features of construction and combinations of parts to be hereinafter described, 25 and finally pointed out in the claims.

In the accompanying drawings, Figure 1 represents a perspective view of my improved combination trunk and dressing-case shown in closed condition and standing on one end. 35 Fig. 2 is a perspective view of the same, showing the trunk with the lid supported in vertical position on one end of the body of the trunk to form a dressing-case; and Fig. 3 is an enlarged vertical transverse section on line 3 3, Fig. 2, drawn on a larger scale.

Similar letters of reference indicate corresponding parts.

Referring to the drawings, A represents the body of the trunk, which is constructed in the usual manner, the corners being reinforced by metallic corner-pieces a a. In the body of the trunk a number of drawers B are arranged, which are provided with drawer-pulls b b, said drawers being guided in suitable guide-strips, similar to drawers in furniture. The body of the trunk also has several compartments B', closed by doors b'.

Various articles can be readily stored in the drawers and conveniently removed by opening the same. The lid D is connected with the body of the trunk by means of steel straps C C, which are hinged to one end of the body of the trunk at C' and riveted to the adjacent end of the lid. The lid is likewise reinforced at the corners by metallic corner-pieces d and 55 provided with a number of compartments D', a hinged looking-glass D², that extends over some of the compartments, and a hinged shelf E below the same for toilet articles and other accessories. The lid D is adapted to be 60 swung by means of the hinged straps C C into position over the trunk-body, in line with the bottom of the same, as shown in Figs. 2 and 3, so that thereby a dressing-case is formed. When the lid is placed in closed position over 65 the trunk-body, it is connected thereto by means of leather straps f on the body, that are passed through rings f' and applied by short straps f² to the front ends of the lid, the lid being further connected to the body of 70 the trunk by means of metal catches and locks, so that a reliable locking connection 75 between the lid and body of the trunk is obtained.

When it is desired to pack the trunk, the 80 body of the same is placed in vertical position on one end and the lid then swung into vertical position on the opposite end of the same. In this position the drawers can be 85 readily filled with the clothing or other articles to be packed in the trunk. When the packing is accomplished, the lid is moved down again over the body of the trunk, the compartments of the same being first likewise filled and closed, so as to retain the articles in the same. The lid is then placed in 90 position on the trunk-body and the latter turned over upon its bottom, when the lid can be readily strapped and locked to the trunk-body in the manner before described. 95

The combined trunk and dressing-case is further provided with leather or other handles g at the sides, so as to be conveniently carried. When the trunk is to be used as a dressing-case, it is placed in upright position 100 on one end and the lid opened and placed in vertical position in line with the bottom of the body, as shown in Fig. 2, in which position the drawers of the body are readily ac-

cessible, so that the trunk can be conveniently used as a dressing-case, in connection with the looking-glass and bracket-shelf of the lid.

5 As the point of hinging the straps C C to the end of the trunk is located near the middle of said end, and as the straps are considerably elongated in front of the lid, it will be seen, when the lid is moved into vertical position upon the end of the trunk-body, that a considerable available surface is afforded by the said end of the trunk in front of the lid, which surface can be utilized as a sort of shelf or mantel for supporting various articles.

15 Having thus described my invention, I claim as new and desire to secure by Letters Patent—

1. A combined trunk and dressing-case, consisting of a trunk-body provided with 20 drawers, a lid, and straps projecting from one end of said lid to a considerable distance in front thereof, said straps being hinged near

the middle of one end of the trunk-body, so that the lid is adapted to be supported in vertical position on the rear part of one end 25 of the trunk-body, substantially as set forth.

2. A combined trunk and dressing-case, composed of a body provided with a number of drawers, a lid provided with compartments, looking-glass and a shelf, straps attached to 30 one end of the lid and projecting a considerable distance in front thereof, said straps being hinged near the middle of one end of the trunk-body, and fastening devices at the front and rear of the body and lid for attaching the lid firmly to the body, substantially as set forth.

In testimony that I claim the foregoing as my invention I have signed my name in presence of two subscribing witnesses.

ERNEST WITTEBORG.
